UNITED STATES PATENT OFFICE

CLIFFORD E. COLE, OF BIRMINGHAM, ALABAMA, ASSIGNOR, BY MESNE ASSIGNMENTS, TO NINETEEN HUNDRED CORPORATION, OF BINGHAMTON, NEW YORK, A CORPORATION OF NEW YORK

CHURN

Application filed January 21, 1929. Serial No. 334,085.

My invention relates to churns, more particularly to churns which are adapted for attachment to household washing machines provided with oscillatory driving posts, and has for its object the provision of apparatus of the character designated which shall be simple of construction and operation, readily cleaned, and which shall be adapted for use with washing machines having various sizes of driving post heads.

A further object of my invention is to provide a churn for use with household washing machines having oscillatory driving posts and wherein the torsional strain on the churn and on the driving post is reduced to a minimum.

A still further object of my invention is to provide, in a churn adapted for use with a washing machine having an oscillatory driving post, an interchangeable coupling member for driving the churn whereby the churn may be readily adapted for use with various makes of washing machines.

A still further object of my invention is to provide an oscillatory churn with an improved removable dash which shall be effective to provide thorough agitation for the cream, when the churn is in operation.

Various kinds of churns have heretofore been provided for use with household washing machines. These churns may be divided into two general classes, the first wherein the cream container is made stationary and means are provided for attaching a dash element to the oscillatory shaft to agitate the cream, and the other wherein the cream container is made movable with the oscillatory shaft and is provided with vanes secured to the body of the container for imparting agitation to the cream at the start and stop of the oscillatory movement of the container.

It is to this latter class of churns that my invention relates. While this class of churns has given eminent satisfaction in use, difficulties have been encountered in their operation due to excessive torsional strain upon the connection between the vessel and the driving post and also due to the fact that the integral dash elements render the cream container

more or less difficult to clean. It is furthermore very desirable in devices of this kind to provide a churn which may be readily adapted for use with different makes of washing machines and thus avoid the necessity of carrying a separate line of churns for each make of washing machines with which they are to be associated.

All of these and other difficulties are overcome by apparatus made in accordance with my invention and illustrated in the accompanying drawings, wherein

Fig. 1 is a vertical sectional view of the apparatus;

Fig. 2 is a transverse sectional view taken along the line II-II of Fig. 1;

Fig. 3 is a sectional view along the line III-III of Fig. 1 and looking in the direction of arrows;

Fig. 4 is a view of the cover for the hollow post of the cream container; and

Fig. 5 is a sectional view of the dash taken along the line V-V of Fig. 1.

Referring now to the drawings for a better understanding of my invention, my improved churn comprises a cream container 10 provided with a suitable cover 11 and having a bottom 12 through which extends upwardly a hollow sleeve 13 through which motion is transmitted to the container. The container 10 is preferably made of metal and the hollow sleeve 13 is designed to better withstand torsional strain by providing an upward bulge to the bottom 12 and by providing a conical brace 14 which is secured to the bottom 12 and is provided with a central aperture having its sides secured to the post 13 in any suitable manner, for example, by welding. The cover 11 is provided with a sight glass 15 through which the churning operation may be seen without stopping the vessel.

The hollow post 13 is provided with a cover 16 having an angular head 17 and having depending marginal lugs 18. The cover 16 fits snugly within the hollow post 13 and is secured thereto by soldering or welding so as to make a smooth, fluid tight joint. Centrally on the lower side of the cover 16 is a squared lug 21 provided with a tapped hole 22 in which fits a screw 23.

Fitting within the lugs 18 is a cup shaped coupling member 24 provided with a central aperture 26 fitting over the central lug 21 of the cover 16. The coupling member 24 is held in place by the screw 23, a washer 27 being interposed between the coupling member and the lug.

The coupling member 24 fits over a head 31 of an oscillatory driving post 32 of a household washing machine such as is employed in a number of well known makes of washing machines. The size and shape of the heads 31 are different in the different makes of washing machines and it will be apparent that coupling members 24 may be in different sizes and shapes to accommodate the different size and shapes of driving post heads and a churn be adapted for association with any one of the several makes by simply attaching to the cover 16 the appropriate size coupling member 24.

Fitting over the squared head 17 of the coupling member is a transverse dash supporting member 36 having a central opening 37 shaped to fit the head 17. For convenience of manufacture, the member 36 is preferably made up of two pieces of strap material secured together and carrying between their outer ends dash elements 38 and 39. The dash elements 38 and 39 extend upwardly to the maximum level of the cream so as to insure agitation thereof and are positioned outwardly near the wall of the container. Extending across the top of the dash elements 38 and 39 and secured thereto by welding is a channel shaped dash element 40. The function of the dash element 40 is to deflect the cream downwardly at the beginning and ending of the oscillatory movement when it is being forced upwards along the elements 38 and 39.

It will be seen that as the driving post 32 oscillates, the vessel 10 and dash elements 38 and 39 oscillate with it. It will furthermore be seen that each time as the oscillatory movement starts and stops, agitation is provided for the cream in the container 10 by its impact with the dash elements 38 and 39 and is deflected downwardly by the dash element 40. These dash elements being secured to the head 17 through the member 36 the major portion of the torsional strain is transmitted directly to the driving post 32 through the cap 16 and coupling member 24 and a minimum of strain is imposed on the sleeve 13 as is the case where the dash is integrally secured to the walls of the vessel. It will furthermore be seen that, as the oscillatory movement starts and stops, less torsional strain is imposed on the hollow sleeve 13 than would be imposed thereon with dash elements integral with the container.

From the foregoing description, the operation of my improved apparatus will be readily understood. The dash being fitted on the head 17 and the vessel 10 being filled with

cream to be churned, the hollow sleeve 13 is lowered over the driving post 32 with the head 31 fitting in the cup shaped coupling member 24. Power is applied to the driving post 32 to impart thereto an oscillatory motion, as is well understood, whereupon the vessel 10 and dash elements 38, 39 and 40 oscillate in unison with the driving post 32. Due to the inertia of the cream within the vessel 10, it is subjected to violent agitation at each beginning and ending of the oscillatory movement so that butter is quickly obtained from the cream. When the churning operation has been completed, the contents may be removed, the dash removed from the head 17 and the interior of the churn be readily cleaned. By providing suitable coupling elements 24, the churn may be adapted for use with various makes of washing machines having different sized driving post heads.

From the foregoing it will be apparent that I have devised an improved churn attachment for washing machines which is simple of design and easy of manufacture and which reduces torsional strains on the driving mechanism to a minimum.

While I have shown my invention in but one form, it will be obvious to those skilled in the art that it is not so limited but is susceptible of various changes and modifications without departing from the spirit thereof, and I desire therefore that only such limitations shall be placed thereupon as are imposed by the prior art or as are specifically set forth in the appended claims.

What I claim is:

1. A churn comprising, in combination, a cream container having a central sleeve rigid therewith adapted to enclose an upright driving shaft, an independently removable dasher element, and a coupling device comprising a cover closing the top of said sleeve and secured thereto, an angular lug formed on the underside of said cover, a coupling element having an angular opening fitting over said angular lug, means for detachably securing said coupling element to said lug, said coupling element being constructed to form a driving connection with said driving shaft to oscillate the cream container, and an angular projection on the top of said cover constructed to form a driving connection with said dasher element.

2. A churn comprising, in combination, a cream container having a central sleeve rigid therewith and adapted to enclose an upright driving shaft, an independently removable dasher element, and a coupling device comprising a cover closing the top of said sleeve and secured thereto, a coupling element detachably secured to the underside of said cover and adapted to be seated upon the top of said driving shaft to support the weight of the churn, said coupling element being constructed to form a driving connection with

- said driving shaft to oscillate the cream container, and a lug formed on the top of said cover and constructed to support and to form a driving connection with said dasher element.
5. 3. A churn comprising, in combination, a cream container having a central sleeve rigid therewith and adapted to enclose an upright driving shaft, an independently removable dasher element, and a coupling device comprising a cover closing the top of said sleeve and secured thereto, a coupling element detachably secured to said cover and constructed to form a driving connection with said driving shaft to oscillate the cream container, and a lug integral with said cover and constructed to form a driving connection with said dasher element.
10. 4. A churn comprising, in combination, a cream container having a central sleeve rigid therewith and adapted to enclose an upright driving shaft, an independently removable dasher element, and a coupling device comprising a cover secured to the top of said sleeve, a coupling element secured to said cover and constructed to form a driving connection with said driving shaft to oscillate the cream container, and means on the top of said cover constructed to form a driving connection with said dasher element.
15. 5. A churn comprising, in combination, a cream container having a sleeve rigid therewith and surrounding an upright driving shaft, an independently removable dasher element, and a coupling device comprising a cover secured to the top of said sleeve and constructed to form a detachable driving connection with said dasher element, and a coupling element detachably secured to said cover and constructed to form a detachable driving connection with said driving shaft to oscillate the cream container.
20. 6. A churn comprising, in combination, a cream container having a central sleeve rigid therewith and adapted to enclose an upright driving shaft, an independently removable dasher element, and a coupling device comprising a cover rigid with said sleeve and constructed to form a driving connection with said driving shaft to oscillate the cream container, and means on said cover constructed to support and to form a driving connection with said dasher element.
25. 7. A coupling device for forming a detachable driving connection between a shaft and a sleeve enclosing the end of said shaft comprising, in combination, a cover secured to the end of said sleeve, and a coupling element detachably secured to said cover and forming a detachable driving connection with the end of said shaft.
30. 8. A coupling device for forming a detachable driving connection between a shaft and a sleeve enclosing the end of said shaft comprising, in combination, a cover secured to the
- end of said sleeve and having an inwardly projecting lug, a coupling element forming a detachable driving connection with said shaft and having an opening fitting over said lug, and means detachably securing said coupling element to said lug.
35. 9. A churn comprising, in combination, a cream container having a bottom and a vertical side wall rising therefrom, and a vertical sleeve fixed to the bottom and rising centrally within the cream container, said sleeve being adapted to pass downwardly over the upper end of an upright driving shaft, and a coupling device comprising a cover closing the top of said sleeve and secured thereto, and a coupling element detachably secured to the underside of said cover and constructed to form a detachable driving connection with said shaft.
40. 10. A churn comprising, in combination, a cream container having bottom and side walls and a vertical sleeve fixed to said bottom and rising centrally within the container, said sleeve having a closure at its upper end and being adapted to be passed downwardly over the upper end of an upright driving shaft, and a coupling element detachably secured within said sleeve and constructed to coat with a complementary part of said driving shaft to provide a detachable driving connection between the churn and said shaft which permits the churn as a unit to be removed from said shaft by a vertical lifting movement.
45. 11. A churn comprising, in combination, a cream container having bottom and side walls and a vertical sleeve fixed to said bottom and rising centrally with the container, said sleeve having a closure at its upper end and being adapted to be passed downwardly over the upper end of an upright driving shaft, an independently removable dasher element constructed to form a driving connection with the closure of the sleeve, and means detachably secured within said sleeve and constructed to form a detachable driving connection with said shaft which permits the churn as a unit to be removed from said shaft by a vertical lifting movement.
50. In testimony whereof I affix my signature.
- CLIFFORD E. COLE.
